CLAIM

The ornamental design for a dual container assembly, as shown and described.

DESCRIPTION

FIG. 1 is a perspective view of a dual container assembly, showing our new design;

FIG. 2 is a front elevation view thereof;

FIG. 3 is a rear elevation view thereof;

FIG. 4 is a left side elevation view thereof, the right side elevation view is a mirror image thereof;

FIG. 5 is a top plan view thereof;

FIG. 6 is a bottom plan view thereof;

FIG. 7 is a cross-sectional view along cross-section line 7-7 of FIG. 5; and,

FIG. 8 is an exploded perspective of the dual container assembly.

1 Claim, 6 Drawing Sheets
